Primary Examiner — Bridget L Eland

Assistant Examiner — Lauren McVey

(57) **CLAIM**

The ornamental design for a label printer, as shown and described.

DESCRIPTION

FIG. 1 is a front, top and right side perspective view of a label printer showing our new design;

FIG. 2 is a rear, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines immediately adjacent to the shaded areas, encompassing unshaded regions, represent the bounds of the claim, while all other broken lines are directed to environment and are for illustrative purposes only; the broken lines form no part of the claimed design.

1 Claim, 7 Drawing Sheets
